UNITED STATES PATENT OFFICE.

JOHN F. PAGENDARM, OF SAN FRANCISCO, CALIFORNIA, ASSIGNOR OF ONE-HALF TO
WILLIAM H. BINNS, OF SAN FRANCISCO, CALIFORNIA.

MOTION-TRANSMITTING DEVICE.

976,907.

Specification of Letters Patent. Patented Nov. 29, 1910.

Application filed November 20, 1909. Serial No. 529,073.

To all whom it may concern:

Be it known that I, JOHN F. PAGENDARM, a citizen of the United States, and a resident of the city and county of San Francisco and State of California, have invented new and useful Improvements in Motion-Transmitting Devices, of which the following is a specification.

The object of this invention is to maintain the equilibrium between the pressure side and the return side in the transmitting column or body of fluid in motion transmitting devices of the kind or description in which pistons or like parts working in cylinders transmit motion by their action against or upon the fluid; and especially to restore the conditions in the column or body of fluid necessary to transmit motion or act upon the parts to be moved in a uniformly positive manner, as often as the same are affected by a loss of fluid and the admission of air by leakage between the pistons and cylinders or at the joints of the fluid holding conductors.

The invention is especially applicable to the type of motion transmitting devices for which Letters Patent of the United States No. 860,619 were issued to me on the 16th day of July, 1907; and in describing the nature of the present invention and the manner of applying and carrying out the same, I shall in the following description explain at length the construction of a motive transmitting device of the type embraced in that patent, to which this invention is applied, that the manner in which I attain the described end and object may be clearly understood and the invention readily applied to any motion transmitting device of the same or a similar type.

The accompanying drawing illustrates the principal parts of a motion transmitting device employing a non-compressible fluid for the transmitting medium, comprising two cylinders and pistons situated respectively at the point or station where the actuating force or power is applied, and at the opposite or distant station where the part or mechanism to be actuated is located.

The pistons and cylinders comprising the motor at the power end or station of the apparatus are formed as segments of a circle with the operating shaft at the center, and they are reversely arranged with re-

spect to each other and also to the corresponding cylinders and pistons of the motor at the opposite station. The pistons are fixed or stationary, and the cylinders are the moving parts; those in each motor being fixed or connected to a common shaft, so as to be moved simultaneously and with equal movement through a partial rotation of the shaft.

The actuating force or power is applied to the shaft either directly by a hand-crank on the shaft, if manual power be employed, or by connecting the shaft with a power driven shaft by suitable mechanical means that will operate the cylinders and pistons relatively to each other with an oscillatory movement at required moments or intervals.

The motor at one end is connected with the motor at the opposite end in the present construction by a pipe or fluid-tight conductor extending into the space in each cylinder of the motor at the other station, and the cylinder spaces thus connected through the conductors and through the pistons—which are hollow for that purpose—are filled with the fluid.

By reason of the reversed arrangement of the motor at one end with respect to that at the other end of the confined column of fluid, it will be seen that in one of the cylinders of the motor to which the power is applied the fluid confined between its closed end and its piston will be forced out and will correspondingly move the cylinder in the opposite motor with which it is connected, by virtue of the hydraulic pressure transmitted through the column of fluid confined in the conductor between the cylinders. But the remaining cylinders in the two motors being reversely arranged with relation to the first mentioned cylinders they act to transmit the motion in the opposite direction when the power operated motor is reversed. By virtue of this arrangement it will be seen that the fluid actuates the part to be moved, or applies the force or power thereto, according to the direction in which the power actuated shaft may be moved; and one side or the other side of the column or body of fluid becomes, so to speak, the pressure side, according as the power operated shaft is turned forward or backward. The fluid in the other side at such time performs no active work, but merely is ex-

elled or transferred from the cylinder at one end to the connected cylinder at the opposite end.

In a motor of this type it is obviously necessary to keep the cylinder spaces and conducting passages between the power operated motor and the one at the opposite end free from air and properly filled with the transmitting fluid; for if the body of fluid 10 on the pressure side or in front of the piston in the power actuated cylinder becomes reduced by leakage, owing to defects in construction or through wear of parts, the disturbance or change of conditions in the body 15 of transmitting fluid will affect the equality or equilibrium between the actuated and the actuating side of the apparatus, and instead of imparting a positive movement to the mechanism or one of corresponding length 20 or duration to the power actuated motor, there will be more or less lost motion, increasing often to such an extent as to render the device in time practically inoperative.

The present improvement consists in reducing 25 the loss and restoring the conditions in the cylinder spaces and fluid holding passages as often as the same are disturbed or unbalanced to such a degree as to affect the character or extent of the movement of the 30 actuated part; and the same is carried out by establishing communication between the fluid containing spaces and passages on opposite sides of the motors at the end of the working or power transmitting stroke, so 35 that on the return throw or movement in the contrary direction the air will be expelled and the loss replaced from the body of fluid with which the cylinder spaces are connected in the movement of the parts.

40 Figure 1 is a longitudinal sectional-view of the power actuated motors and their inclosing casing in that part of the apparatus in which the power applied through the confined transmitting fluid is caused to actuate the parts to be moved. Fig. 2 is a similar 45 longitudinal sectional view of the motor and its casing at the opposite or distant station where the mechanism to be operated is located. Fig. 3 is a front-view of the motor 50 shown in Fig. 1, showing the cover or front plate of the casing removed to expose the parts within. Fig. 4 is a sectional-view similar to Fig. 2, illustrating a slight modification of the means for establishing communication between the opposite sides of the fluid-containing spaces and passages, wherein such communication is opened or closed directly by the piston itself, instead of by a separate valve. In this arrangement the 55 pistons have the function of a valve. Fig. 5 illustrates one application of the invention to a type or construction of motor in which straight cylinders and pistons are employed in place of quadrant shaped or curvilinear 60 ones.

The type of motor illustrated in the drawings is applicable, for operating a door opener and closer, for handling and controlling a rudder, or for operating with a positive movement a part or mechanism from a point 70 or station distant from the operator, and as applied to a motor of that construction this invention is carried out by connecting the spaces in the associated cylinders of the motor with a body of fluid confined in a 75 fluid tight case by ports or apertures in the cylinders, so arranged that communication 80 between the cylinder spaces and the fluid holding space or chamber in the case is set up or established when the movement of each piston with relation to its cylinder 85 brings the aperture in front of the piston in the return stroke. At some point in that stroke or movement, therefore, the fluid confined in the cylinder is put directly in communication with the fluid in the case for a sufficient period to displace the air and restore the conditions in the pressure transmitting fluid throughout the entire length of conductors or connecting passages between 90 the two motors.

At that end of the apparatus where the power operated motor is situated the motor herein illustrated is composed of the cylinders *a*—*b* and the pistons *e*—*f*, arranged 95 side by side and also placed in reversed relation, or so that one piston will move out from its cylinder at the same time that the other piston moves into its associated cylinder and with an equal movement, and the 100 case *g* containing the restoring or equalizing fluid is arranged to inclose the cylinders.

The shaft 2 on which the cylinders *a*—*b* are fixed by their hubs 3 is movable in an arc of 90° or thereabout, which is the extent of movement necessary to operate the motors; and the cylinders *c*—*d* at the opposite station are fixed on a common shaft 4 in like reversed relation and are similarly inclosed in a fluid tight casing *g* and are 110 connected with the fluid holding space of the case through apertures 12; the shafts of both motors being carried outside through suitable stuffing boxes in the sides of the case.

The shaft 4 can be connected with the part to be moved or operated through the medium of gears, levers, or other well known mechanical means to convert the movements of the shaft into reciprocatory motion; or to 120 vary the movement, if of a rotary character.

In the present construction of motor the pistons are fixed or stationary, being formed practically as terminals of the fluid conductors, to which end they are hollow; or are 125 provided each with a tubular passage opening through the piston head and ending in or at a nipple 6 to which the fluid conducting pipe 8 is connected by a coupling 10. The pistons *e*—*f* are separately connected in 130

this manner by the pipes 8-9 with the pistons *h-i* in the opposite motor, and both the cylinder spaces in front of the pistons and the connecting pipes or passages between the two motors are filled with a mixture of water and glycerin, or with oil, or some other suitably non-compressible fluid. By virtue of the arrangement of the cylinders *a-b* and their pistons in reversed relation to each other, and to the cylinders *c-d* and their pistons, and the similar reversed relation of the cylinders *e-f* to each other, the motor cylinder *a* has the effect to transmit motion through the body of confined liquid and thereby produce a relative movement of the cylinder and piston *c-h* and through those parts move the shaft 4 in one direction; and if the spaces and passages be properly filled with the transmitting fluid the shaft 4 will respond promptly and its motion will be equal to the motion of the shaft 2. But owing to defects in construction, and particularly to wear of surfaces between the piston heads and the surrounding walls of the cylinders, a greater or less extent or degree of lost motion is liable to result from loss of fluid by leakage and thereby destroy or materially reduce the efficiency of the apparatus. In the present invention any loss of fluid taking place in the pressure side of the apparatus, however slight it may be, at each time of operation is replaced from the body of fluid in the case by virtue of the communication set up between the cylinder space in front of the piston and the body of fluid in the case at the end of every stroke or movement of the cylinder relatively to the piston, so that in the following stroke or movement the pistons will always act against a solid body of fluid.

Communication between the cylinder space in front of the piston—or the pressure side—and the fluid holding space in the casing is provided through the aperture 12 in the cylinder, and is controlled either directly by the piston itself, as in Fig. 4, or through the medium of a valve actuated mechanically by or through the movements of the cylinder or its piston, as in Figs. 1 and 2.

In one way the port or aperture 12 is situated at or near the head of the cylinder, as seen in Figs. 1 and 2, and is controlled by a puppet valve 13 held to a seat in the opening by a spring and actuated by an incline or fixed piece 14 situated in the path described by the projecting end of the valve-stem 15. Provision is made for varying the movement of contact between the valve-stem and this incline, by making the incline 14 adjustable with relation to the end of the valve-stem, such as by a screw-stem 16 extending through the casing to the outside, whereby the wedge 14 may be set to make contact with the valve-stem at a period

earlier or later in the movement of the cylinder. Or, it can be set out of operative position altogether when the conditions existing in the pressure side do not require to be changed, and the valve may remain closed. By locating this aperture 12 in the cylinder at such distance from the open end of the cylinder that at the end of the stroke communication will be set up between the cylinder space in front of the piston and the fluid in the case, the mechanically operated valve can be dispensed with. The periods of setting up and of cutting off communication between the confined column or body of transmitting fluid and the fluid in the case will thus be controlled directly by the piston.

Fig. 5 illustrates the mode in which the last mentioned means of restoring the equilibrium between the two sides of the power transmitting fluid is applied to an apparatus in which the cylinders are arranged in a straight line for operation with a reciprocating double end piston. In an apparatus of that type the ends of the cylinder are partly inclosed in a fluid tight casing 18 and the pistons are connected by a rack and pinion with a power operated shaft as a convenient means of reciprocating the piston from the oscillatory or partially rotary motion of the shaft.

Provision can be made for maintaining a uniform body of fluid in the case and keeping the same properly filled, as well as to afford an outlet for particles of air that may be displaced from the fluid holding spaces and passages, by connecting the case with a fluid holding receptacle such as a stand pipe or a tank 20 by means of a tube 21.

I claim:—

1. In a device operating to transmit motion through the medium of a non-compressible fluid and having a motor piston and cylinder to which the motive force or power is applied, and a piston and cylinder operatively connected therewith by a body of non-compressible fluid, a fluid tight case containing a body of fluid and means operating in the movements of the said cylinders and pistons with relation to each other for opening communication between the body of fluid under pressure of the transmitting force or power and the confined body of fluid in the case.

2. In a motion transmitting device adapted to operate through the medium of a body of non-compressible fluid, the combination of a motor piston and cylinder movable relatively to each other, a similar cylinder and piston reversely arranged with respect to the first named cylinder and piston and actuated thereby and means for actuating the said cylinders and pistons relatively to each other, comprising a non-compressible fluid contained in passages and connecting the cylinder spaces in front of the pistons in

4
one motor with corresponding spaces in the cylinders of the motors to be actuated, a fluid tight case inclosing the cylinders and their pistons, and means operated by the movement of the piston in each cylinder to set up or shut off communication between the case and the cylinder spaces at a predetermined period in such movement.

3. In a motion transmitting device, an actuating motor having reversely arranged cylinders and pistons therein movable relatively to the cylinders, and adapted to transmit their motion through a non-compressible fluid according to the direction in which the motive force is caused to actuate the said cylinders and pistons, the combination therewith of a fluid tight case connecting said cylinders and means operating to alternately open and close communication between the cylinder spaces and the fluid holding space in the case at predetermined periods in the operation of the motor.

4. In a motion transmitting device operating through the medium of a non-compressible fluid, a motor having reversely arranged cylinders and pistons therein movable relatively to the cylinders, one of said cylinders operating to expel and the other to simultaneously fill with the transmitting fluid, and means operating to maintain a condition of equilibrium in the fluid acted on by the two pistons and cylinders, including a fluid tight case and means operating by the movements of the pistons in their respective cylinders to alternately set up and shut off communication between the cylinders and the said case at a predetermined period in their movement.

5. The combination with a motor comprising cylinders reversely arranged and pistons therein movable relatively to the cylinders, of fluid carrying passages connecting separately the cylinder spaces with the parts adapted to be actuated by the hydraulic pressure transmitted through the fluid, and means for replacing loss of fluid in the said passages, comprising apertures in the cylinders and a fluid tight casing common to

said cylinders with which said apertures are arranged to communicate when opened, and means operating through the movements of the pistons with relation to the cylinders to shut off communication in the working stroke of said parts.

6. The combination with a motor having reversely arranged cylinders and associated pistons, of a fluid tight case inclosing the same, and means operating in the movements of the cylinders and pistons with relation to each other to establish communication between the cylinder space in front of the piston and the surrounding case in the return stroke and to cut off such communication in the working stroke of the motor.

7. The combination with a motor having reversely arranged cylinders and associated pistons, of a fluid holding case, and means operating in the movements of the cylinders and pistons relatively to each other to establish communication between the cylinder spaces in front of their pistons through the body of fluid in the case in the movement of said parts in one direction and to cut off such communication between the cylinders in the working strokes thereof.

8. In a fluid motor having reversely arranged cylinders and associated pistons operating through the medium of a column of fluid connecting the cylinder spaces with mechanism adapted to be operated by the hydraulic pressure transmitted through the fluid, the combination with the cylinders of a fluid filled case and means through which the cylinder spaces in front of the pistons are connected together through the body of fluid confined in the case at predetermined periods in the movements of the pistons in the cylinders, comprising apertures in the cylinders and means operated by the movement of said parts to control the periods of opening the cylinder spaces to the case through said apertures.
